CPC D06F 39/045; D06F 29/00; D06F 29/005;
D06F 25/00; D06F 39/022; D06F 33/02;
1. Prewashing sink for washing machine
1.1 is a perspective view of a prewashing sink for washing machine showing our new design;
1.2 is a front elevation view thereof;
1.3 is a rear elevation view thereof;
1.4 is a left-side elevation view thereof;
1.5 is a right-side elevation view thereof;
1.6 is a top plan view thereof;
1.7 is a bottom plan view thereof; and
1.8 is a perspective view thereof in a use condition.

The broken lines in Figure 1.8 illustrating portions of the washing machine form no part of the claimed design.
